198,997
BOTTLE

John Brady Campbell, Paramus, N.J., assignor to The Procter & Gamble Company, Cincinnati, Ohio, a corporation of Ohio

Filed Feb. 19, 1964, Ser. No. 78,692

Term of patent 14 years
(Cl. D58—6)

FIG. 1 is a front elevational view of a bottle showing my new design.

FIG. 2 is a side elevational view of the same.

FIG. 3 is a cross-sectional view of the same, taken on the line 3—3 of FIG. 1.

FIG. 4 is a cross-sectional view of the same, taken on the line 4—4 of FIG. 1.

FIG. 5 is a cross-sectional view of the same, taken on the line 5—5 of FIG. 1.

FIG. 6 is a cross-sectional view of the same, taken on the line 6—6 of FIG. 1.

FIG. 7 is a cross-sectional view of the same, taken on the line 7—7 of FIG. 1; and

FIG. 8 is a top plan view of the same. The sides not shown are the same as the sides shown.

I claim:

The ornamental design for a bottle, as shown and described.
